F. J. O'NEILL

GAME BOARD

Filed Jan. 8, 1926

UNITED STATES PATENT OFFICE.

FRANCIS J. O'NEILL, OF MILWAUKEE, WISCONSIN.

GAME BOARD.

Application filed January 8, 1926. Serial No. 30,054.

To all whom it may concern:

Be it known that I, FRANCIS J. O'NEILL, a citizen of the United States, residing at Milwaukee, in the county of Milwaukee and State of Wisconsin, have invented a new and useful Game Board, of which the following is a specification.

This invention relates to a game board, one of the objects of the invention being to provide a device of this character with which marbles are to be used as game pieces, the board being provided with an opening constituting a target at which the marbles are to be thrown. Means are employed for accumulating marbles which fail to hit the target and additional means are provided whereby, when a marble enters the hole constituting the target, one or more of the accumulated marbles will be released and thus constitute points to be added to the score of the player.

With the foregoing and other objects in view which will appear as the description proceeds, the invention resides in the combination and arrangement of parts and in the details of construction, hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a plan view of the game board, a portion thereof being broken away.

Figure 2 is a section on line 2—2 Figure 1.

Figure 3 is a section on line 3—3 Figure 1.

Referring to the figures by characters of reference 1 designates a box-like casing preferably open at the bottom and provided at the top close to but slightly below the top edges of the walls of the casing, with an inclined board 2 provided, near its center, with an opening 3 sufficiently large to receive the marbles constituting the game pieces. An inclined trough 4 is arranged along but below the lower edge of the board 2 so as to receive any marbles which may roll off of the board. An opening 5 is formed in the trough near one end thereof, this opening being too small to permit a game piece to fall therethrough. The lower end of the trough is spaced from the adjacent

wall of the casing 1 and is overhung by a deflecting tongue 6.

An outlet opening 7 is provided in one wall of the casing 1 close to the lower end of the trough and leading toward this outlet is a chute 8 which is fastened under the board 2 so as to receive a marble passing through the opening 3 and directly toward the outlet 7.

Pivotedly mounted in a bracket 9 secured to the bottom of the board 2 is a lever 10 having a short arm 11 which is extended under the opening 3. Another arm 12 is extended under the lower end portion of the trough 4 and has a lug 13 extending upwardly therefrom and normally disposed below the opening 5 in the trough. A deflecting wall 14 is mounted on one corner portion of the board 2 close to but above the lower end of the trough 4 so that any game pieces rolling toward the lower end of the trough will be deflected so as to fall onto the trough at a point between the upper end thereof and the opening 5.

In playing the game a marble is tossed onto the board 2 and if it fails to enter the opening 3 it will roll downwardly into the trough 4 and then roll along the trough until it comes to the opening 5 whereupon it will become seated in the opening as shown in Figures 2 and 3 wherein the marble has been shown at M. Other marbles are then used and each time the opening 3 is missed, the marble will roll into the trough 4 and remain therein back of the marble which is located in the aperture 5. Thereafter should one of the marbles drop through the opening 3 it would strike the arm 11 of lever 10 and cause it to swing downwardly. Thus said marble will drop into the chute 8 and roll downwardly to the outlet 7. At the same time the arm 12 of the lever will be swung upwardly so that the lug 13 will come against the bottom portion of the marble M which is seated in opening 5 and will lift said marble from the opening. Thus the marble will be permitted to roll off of the end of the trough 4 and drop into the lower portion of the chute 8 so as to pass into the opening 7. Consequently the player will be credited with the marble which was thrown through the opening 3 and also the marble which was released from the opening 5.

Another marble will take the place of the one dislodged from the opening 5 so that the device is thus reset. The deflecting strip

6 serves to prevent the marble 5 from being thrown upwardly off of the board.

As shown in the drawings the board 2 can be provided with a covering 15 of a soft fabric.

What is claimed is:

1. A game board including a casing having an outlet opening at the bottom thereof, an inclined board in the casing provided with an opening for the reception of a game piece, an inclined trough along the lower edge of the board for receiving game pieces therefrom, said trough having an aperture adjacent one end for receiving and retaining a game piece directed thereto by the trough, and means operated by the dropping of the game piece through the opening in the board for lifting a retained game piece from the aperture in the trough.
- 10 2. In a game board the combination with a casing, of an inclined board having an opening for the reception of a game piece, an inclined trough along the lower edge of the board provided with an aperture for receiving and retaining a game piece, a lever fulcrumed between its ends below the board and having one arm extending under the opening in the board and the other arm extending under the aperture in the trough, said lever constituting means for actuation by a game piece directed through the opening in the board, and means on the lever for lifting a game piece from the aperture in the trough when the lever is actuated.
- 15 3. A game board including a casing having

an outlet opening at the bottom thereof, an inclined board in the casing provided with an opening for the reception of a game piece, an inclined trough along the lower edge of the board for receiving game pieces 40 therefrom, said trough having an aperture adjacent one end for receiving and retaining a game piece directed thereto by the trough, means operated by the dropping of the game piece through the opening in the board for lifting a retained game piece from the aperture in the trough, and means overhanging a portion of the trough for holding the released game piece against upward ejection from the casing.

4. A game board including a casing having an outlet opening at the bottom thereof, an inclined board in the casing provided with an opening for the reception of a game piece, an inclined trough along the lower edge of the board for receiving game pieces therefrom, said trough having an aperture adjacent one end for receiving and retaining a game piece directed thereto by the trough, means operated by the dropping of the game piece through the opening in the board for lifting a retained game piece from the aperture in the trough, and means for directing game pieces from the opening and aperture to the outlet.

In testimony that I claim the foregoing as my own, I have hereto affixed my signature.

FRANCIS J. O'NEILL.
